ADAM H. SHEARER, OF YORK, PENNSYLVANIA.

SECTIONAL BED FRAME.

1,405,721.

Specification of Letters Patent. Patented Feb. 7, 1922.

Application filed April 14, 1920. Serial No. 373,888.

To all whom it may concern:

Be it known that I, ADAM H. SHEARER, a citizen of the United States, residing at York, in the county of York, State of Pennsylvania, have invented certain new and useful Improvements in Sectional Bed Frames; and I do hereby declare the following to be a full, clear, and exact description of the invention, such as will enable others skilled in the art to which it appertains to make and use the same.

This invention relates to bed bottoms of fabric, and more especially to the frames thereof which are made in sections so that they may be folded; and the object of the same is to produce an improved hinge connection for use at the meeting ends of the sections of the head rail and foot rail.

The invention consists in a hinge specially constructed for use at this point. Referring to the accompanying drawings:

Figure 1 is a perspective view of one end of a two-part spring bed, showing its sections as connected by this improved hinge and as opened out.

Figure 2 is a section on the line 2—2 of Figure 1, on an enlarged scale.

Figure 3 is a detail of the members of the hinge.

30 The numerals 10 and 11 denote a pair of hinged bed sections, each consisting of two tubular side rails 12, knees or risers 13 at their ends, and angle iron cross rails 14 carried by the upper ends of the knees, and to 35 and between which the fabric 15 is stretched as usual. If we assume that the entire structure is of the width of the ordinary double bed, then each section should be half that width and the ends of the head and foot 40 rails 14 should abut each other when the sections are opened out as seen in Figure 1. But when the structure is to be reduced to smaller compass for storage or transportation, it becomes desirable to fold one section 45 onto the other; and for this purpose the inner portions of abutting end rails are connected by an improved form of hinge which constitutes in this combination the essence of the present invention.

50 The hinge is composed of two leaves whose bodies 20 and 21 are substantially square and pierced with central holes 22, a neck 23 rises obliquely from one corner of the body 20 and a neck 24 from one corner of the body 21, and these necks are deflected a

little out of the planes of their bodies so that they lap each other, their outer ends being rounded as shown, and through the centers of said rounded ends is passed a rivet 25, its head 26 being on what might be called 60 the outer face of the outer neck 24, and its inner end being upset at 27 against the inner face of the inner neck 23. Across the upper edge of the body 20 is a flange 30, this flange 65 extending along the upper edge of the neck 23 as at 33, and around the rounded end of the same as at 37 so that it is continuous of the neck and encloses the upset end 27 of the rivet. Across the upper edge of the other leaf-body 21 is another flange 31, but 70 this flange is carried only part way up the neck 24.

When the leaves of this hinge are applied to the bed-frame structure, their bodies, 20 and 21 are laid against the outer faces 75 of the depending webs of the cross rails 14, and their flanges 30 and 31 respectively upon the upper faces of said cross rails as best seen in Figure 1, their necks at this time extending upwardly and over-lying, with 80 their side faces in mutual contact and the flange portion 37 of the neck 22 directed away from the neck 24. The pivot pin 25 connecting the necks stands directly over the line where the extremities of said cross rails 85 meet. Bolts 39 are now passed through the holes in the leaves, and through alining holes in the depending webs of the rails, and are carried onward through the upper ends of the knees or risers, and their nuts applied. 90 Thus the sections of the head rail and those of the foot rail will be hingedly connected, and the bolts which attach the hinges to the sections will also attach the risers thereto, so that only a single bolt is necessary at each 95 corner of a bed section. The rivet or pivot between the hinges is wholly above the upper faces of the spring bed fabric, and when the bed is to be folded one section can be swung completely over onto the other in a manner 100 which will be clear. The rounded upper ends of the necks of the hinge leaves are inconspicuous and made as small as possible, and the bedding will not catch thereon.

The extension of the flange around the head 105 of one leaf gives it additional strength and forms a housing for the upset end of the rivet, so that the clothing cannot catch thereon. It is even possible to substitute a bolt, and set up its nut within the housing 110

thus produced, but as this would be the use of an obvious equivalent, it is hardly necessary to illustrate the same.

It will be understood upon reference to Figures 2 and 3 of the drawings, that the bottom of the flange 37 at the underside of the neck 23, is on a level with the underside of the flange portion 30, so that the bottom of flange 37 likewise rests upon the upper surface of the corresponding cross rail web to give corresponding strength to the structure.

What is claimed is:

The combination with a pair of angle rails disposed with their corresponding webs in end abutting relation of a pair of hinged leaves each including a plate comprising a body secured against the outer side faces of

corresponding webs and having each a flange along an edge disposed upon the other web 20 of its rail, the plates having necks extending beyond those webs upon which their flanges rest respectively, the necks being overlapped and contacting and pivotally connected, the flange of one plate extending continuously of the edge of the neck of that plate and resting at the under side of the neck upon the same rail web with the corresponding body flange of that plate.

In testimony whereof, I affix my signature, in the presence of two witnesses.

ADAM H. SHEARER.
